F. W. BRYSON.
BRICKMAKING MACHINE.
APPLICATION FILED JUNE 12, 1914.

1,236,144.

Patented Aug. 7, 1917.

UNITED STATES PATENT OFFICE.

FRANK W. BRYSON, OF PORTER, INDIANA, ASSIGNOR TO HYDRAULIC-PRESS BRICK COMPANY, OF ST. LOUIS, MISSOURI, A CORPORATION OF MISSOURI

BRICKMAKING-MACHINE.

1,236,144.

Specification of Letters Patent.

Patented Aug. 7, 1917.

Application filed June 12, 1914. Serial No. 844,652.

To all whom it may concern:

Be it known that I, FRANK W. BRYSON, a citizen of the United States, residing at Porter, in the county of Porter and State 5 of Indiana, have invented certain new and useful Improvements in Brickmaking-Machines, of which the following is a specification.

This invention relates to brick making 10 machinery and with regard to certain features thereof to machinery designed for roughening and ornamenting the surface of a brick during the process of making the same.

15 One of the objects of the present invention is to provide a simple and practical machine of the above character which will be cheap to manufacture and install. A further object is to provide a reliable and 20 efficient machine of the above character which will give an artistic and roughened finish to the exposed surface of the brick when placed in position in a wall. Other objects will be in part obvious and in part 25 hereinafter pointed out.

The invention accordingly consists in the features of construction, combination of elements and arrangement of parts which 30 will be exemplified in the device hereinafter described, and the scope of the application of which will be indicated in the following claims.

In the accompanying drawing wherein is 35 shown one of the various possible embodiments of the present invention there is shown in perspective such parts of a complete machine as are necessary to fully understand the present invention.

Referring to the drawing in detail 5 designates a horizontally disposed frame carrying at its opposite ends rollers 6 around which passes an endless belt 7. This belt is supported between the main rollers by a plurality of smaller rollers 8 mounted in 45 the frame and transversely disposed with respect to the path of travel of the belt. This frame is adapted to be positioned adjacent a die outlet 10 through which a clay stream 11 passes. This stream is forced out in any 50 desired manner as by means of screw force feed, and a disclosure thereof is believed to be unnecessary to those skilled in the art. At the opposite end of the belt or conveyer

is positioned a cutting means (not shown) of any desired type, adapted to cut the clay 55 stream into bricks of proper size.

Above the conveyer is mounted an auxiliary frame 12 carrying at one side a transversely disposed shaft, on the end of which is keyed a driving pulley 13 connected by 60 means of a belt 14 with any suitable source of power. Adjacent the driving pulley is a sprocket wheel 15 or other suitable form of power conveying means about which a sprocket chain 16 passes to a second sprocket 65 wheel 17 mounted on a transversely disposed shaft 18 at the opposite end of the auxiliary frame 12. Intermediate the end shafts is a third shaft 20 upon which a wooden roller 21 is mounted, having a polished steel surface 22. This roller is adapted to be lubricated by means of waste or the like contained in a trough 23 positioned thereabove.

The transverse shaft 18 at the right of the frame is provided with a roller 24 having a plurality of projecting pins 25 or the like adapted to scratch or mark the upper surface of the clay stream as it passes thereunder. It will also be noted that this transverse shaft carries a smaller sprocket 80 wheel 26 which may be geared with the driving sprocket wheel 15 when moved to the opposite end of the transverse driving shaft, in order to vary the speed at which the marking roller is rotated.

To the right of the marking device is positioned a second frame 30 pivotally mounted on the upright 31 at each side of the clay stream. This frame carries a roller 32 having a sheep skin surface adapted to rest 90 upon the clay stream with any desired degree of pressure and smooth out projections on the roughened upper surface of the clay stream. The pressure with which this roller acts may be varied by means of weights 33 95 positioned in a trough formed by the fork ends of the uprights carrying this roller. The inclined side of the pressure roller frame forms a screen 34 adapted to catch the small particles of clay that are thrown off 100 by the centrifugal action of the roughening marker roller 24. These particles fall back on the upper surface of the clay stream and are pressed downwardly as the clay stream passes under the pressure roller 32.

105 While the operation and method of use of

this device should be obvious from the above disclosure, a brief statement thereof is as follows:

Assuming the clay stream 11 to be forced 5 out through the die 10 on to the conveyer belt 7, it passes under the lubricated polishing or leveling roller 21 which has previously been adjusted in trunnions 36 at each end to bear with any desired pressure upon 10 the upper surface of the clay stream. The clay stream then passes under the marking roller which is driven counterclockwise at a relatively high speed, that is, much faster than the flow of the clay stream, so that 15 scratches or indentations are made in the upper surface. The small particles of clay removed by the pegs or pins 25 are thrown up on the inclined screen by the centrifugal action of the rotating roller 24, from which 20 they fall back onto the upper surface of the clay stream and are pressed into the roughened surface by means of the pressure roller 32 at the right. The clay stream is then cut into bricks of the desired size and shape 25 by mechanism not shown.

It is thus seen that the present device provides a simple and practical mechanism for finishing or roughening the exposed surfaces of bricks during their manufacture. The 30 device is automatic in its operation and reliable and efficient in use, and accomplishes among others all of the objects and advantages above set forth.

As many changes could be made in the 35 above construction and many apparently widely different embodiments of my invention could be made, without departing from the scope thereof, I intend that all matter contained in the above description or shown 40 in the accompanying drawing shall be interpreted as illustrative and only limited by the appended claims.

Having thus described my invention what I claim as new and desire to secure by Letters Patent is:

1. In a brick making machine, in combination, means for forming a clay stream, a conveyer for the clay stream, a marking roller adapted to be driven at a peripheral 50 speed greater than the rate of movement of the clay, and a pressure roller adapted to apply pressure to the clay after it has passed the marking roller.

2. In a brick making machine, in combination, a conveyer for a clay stream, a marking roller positioned thereabove, means for rotating said marking roller at relatively high speed, a leveling roller at one side thereof, and a pressure roller at the opposite 60 side thereof.

3. In a brick making machine, in combination, a conveyer for a clay stream, rotary means for roughening the upper surface of the stream, an adjustably mounted leveling 65 roller positioned thereabove, a pressure

roller beyond said first roller, and means for adjusting the degree of pressure with which said pressure roller bears on the clay stream.

4. In a brick making machine, in combination, a conveyer for a clay stream, an adjustably mounted leveling roller positioned thereabove, a pressure roller, means for adjusting the degree of pressure with which said pressure roller bears on the clay stream, and a marking roller positioned between the 75 pressure roller and the leveling roller.

5. In a brick making machine, in combination, a conveyer for a clay stream, a frame positioned thereabove, a driving member on said frame, a driven member, a marking roller connected with said driven member comprising a cylindrical roller having a plurality of rows of pegs or pins projecting from the surface thereof and means for smoothing out the markings. 80

6. In a brick making machine, in combination, a conveyer for a clay stream, a frame positioned thereabove, a driving member on said frame, a driven member, a marking roller connected with said driven member comprising a cylindrical roller having a plurality of rows of pegs or pins projecting from the surface thereof, and a pressure roller adapted to apply pressure to the clay after it has passed the marking roller. 90

7. In a brick making machine, in combination, a conveyer for a clay stream, a frame positioned thereabove, a driving member, a driven member, a marking roller connected with said driven member comprising a cylindrical roller having a plurality of pegs or pins projecting from the surface thereof, an adjustably mounted leveling roller adjacent the marking roller, means for lubricating the surface of said leveling 100 roller, and a pressure roller at the opposite side of said marking roller.

8. In a brick making machine, in combination, a conveyer, means for forming a clay stream, a marking roller adapted to be 110 driven at relatively high speed, and means for returning the removed particles of clay to the marked surface of the clay stream.

9. In a brick making machine, in combination, a conveyer, means for forming a 115 clay stream, a marking roller adapted to be driven at relatively high speed, and means for returning the removed particles of clay to the marked surface of the clay stream, said means comprising an inclined 120 screen adjacent said marking roller.

10. In a brick making machine, in combination, a conveyer, means for forming a clay stream, a marking roller positioned thereabove adapted to be rotated at a higher 125 speed than the travel of the clay stream, means for varying the rate of rotation of said marking roller and means for smoothing out said markings in the clay stream.

11. In a brick making machine, in combi- 130

5 nation, a conveyer, means for forming a clay stream, a marking roller adapted to be driven at relatively high speed, means for returning the removed particles of clay to the marked surface of the clay stream, said means comprising an inclined screen adjacent said marking roller, and means for smoothing out said markings in the clay stream.

10 12. In a brick machine, in combination, means for forming a clay stream, and means for forming and depositing upon the upper surface thereof particles of plastic clay for the purpose of ornamenting the surface of said clay stream.

15 13. In a brick machine, in combination, means for forming a clay stream, means for forming and depositing particles of plastic clay upon the upper surface of said clay stream, and means for pressing said particles of clay into firm contact with the surface of said clay stream.

20 14. In a brick machine, in combination, means for forming a clay stream, a marking roller adapted to be driven at a peripheral speed different from the rate of movement of the clay, and means for applying pressure to the clay after it has passed the marking roller.

25 15. In a brick making machine, in combi-

nation, means for forming a clay stream, a marking roller adapted to be driven at a peripheral speed greater than the rate of movement of the clay, and means for applying pressure to the clay after it has passed the marking roller.

30 35 16. The combination with a machine adapted to discharge a continuous column of clay therefrom, of a rotary cutter adapted to remove a portion of the clay from the face of said clay column, said rotary cutter adapted to shred the material thus removed and deposit the particles upon the face of the clay column from which they were removed, and means for causing the loosened particles of clay to adhere to the column.

40 45 17. In a brick making machine, in combination, means for forming a clay stream, a conveyer for the clay stream, a marking roller adapted to be driven at a peripheral speed greater than the rate of movement of the clay, and means adapted to apply pressure to the clay after it has passed the marking roller.

50 In testimony whereof I affix my signature in presence of two witnesses.
